SPUDDING BIT

Ernest L. Potts, Houston, Tex., assignor to Eastman Oil Well Survey Company, Dallas, Tex., a corporation

Application August 31, 1936, Serial No. 98,695

3 Claims. (Cl. 255—64)

The invention relates to a bit to be used in the spudding operation in the drilling of wells and particularly where it is desired to deflect the direction of the well bore.

5 In the drilling of wells it is not uncommon for the direction of the well bore to be deflected so that the well bore bears off at an angle with respect to the vertical or with respect to the intended direction thereof. Such a deflection is 10 detrimental because it increases the difficulty and the cost of drilling and interferes with the positioning of the casing, tubing and pumping equipment in the well. It is, therefore, desirable to normally maintain the direction of the well 15 bore as nearly to the intended direction as possible. In event the well bore is deflected for some reason or other, it is the usual practice to either fill in or plug back the well bore with concrete or to set a whipstock at the elevation 20 where the deflection of the well bore occurred. A suitable milling tool or drill is then used on the whipstock or concrete plug so that in this manner the well is brought back to a vertical or intended direction. In other instances, ob- 25 structions occur in the well bore or pieces of equipment may become lodged in the bore in such a position that the continuation of the bore must be deflected around such obstruction or equipment. In such instances sometimes concrete is deposited about the obstruction and the well bore deflected from the concrete or a whip- 30 stock may be set.

Difficulty has been encountered in both of the 35 above instances in properly deflecting the well bore immediately adjacent the whipstock or the concrete which has been positioned in the well bore. Some of this difficulty has been due to the fact that a rotating bit is used to effect the deflecting action and it is impossible to deter- 40 mine in what direction the deflection is initiated so that one of the objects of the present invention is to provide a spudding bit which will not be rotated but which will be reciprocated in order to effect the deflection of the bore closely 45 adjacent the whipstock or concrete.

It is one of the objects of the present invention to provide a spudding bit by which the direction of the well bore may be changed.

50 Another object of the invention is to provide a spudding bit which is of chisel-like construction so that when pressure is applied to it it will move off at an angle.

Another object of the invention is to provide 55 a chisel bit for spudding operations wherein the

cutting edge is off center and a passage for fluid is provided through the bit.

Still another object of the invention is to provide a chisel bit whose angular position is capable of adjustment.

Other and further objects of the invention will be readily apparent when the following description is considered in connection with the accompanying drawing, wherein

Fig. 1 is a side elevation of the spudding bit 10 with certain portions broken away to illustrate the construction thereof.

Fig. 2 is a view of the front face of the bit showing the construction of the water course and the connection of body and the blade.

Fig. 3 is a section taken on the line 3—3 of Fig. 2 and showing the arrangement for the water passage.

Fig. 4 is a diagrammatic view showing the use of the bit where a straight hole is to be deflected. 20

Fig. 5 is a diagrammatic view of a crooked well which is to be straightened.

In the drilling of wells particularly by the rotary method a drill bit is advanced into the ground by rotation of a drill stem and the circulation of drilling fluid through the drill stem and drill bit. A well bore which has been formed in this manner is illustrated generally at 2 in Fig. 4, and is shown as having been plugged at its lower end by a body of cementitious material 30 such as 3. Various causes for plugging a well in this manner can arise. In some instances the bore may have been drilled into an undesirable formation, such as salt or salt water, and it has been desired to plug off the undesirable formation and to continue the drilling of the well at an angle so that it may be possible to avoid the undesirable formation.

The practice as now followed is to set a whipstock or to set a cement plug such as 3, and to 40 then go into the well bore with a rotating tool which will skid from the top 4 of the cement plug and which will be deflected down along the side of the plug so that the well bore thereafter gradually deviates from the original well bore. 45 The difficulty with bits of this nature which rotate resides in the fact that the operator is unable to control the direction at which the deviation is to occur. That is, looking at the well bore in plan view the deviation may occur in 50 any direction of the compass, which of itself may be undesirable, because in some instances by deflecting the well in a particular direction it may be possible to penetrate some known or desirable formation.

The present construction has been developed with a view of initiating the deflection of the well bore in the desired direction and, as seen in Fig. 4, the spudding or chisel bit 5 is shown as being applied to the top 4 of the cement plug 3 so that the cutting edge 6 thereof will be deflected along the line of the arrow 7, or in other words it can be directed in a controlled manner from the top of the cement plug 3. The spudding bit 5 is operated by the string of pipe 8 and has a swivel or pivot joint 9 therein by which the angular position of the blade 5 with respect to the operating string 8 may be set at any desired angle.

In Fig. 5 the construction of the stem, bit and plug are the same as described in connection with Fig. 3, except in Fig. 5 the well bore 2 is deviated from the vertical at the point 10 and the cement plug 3 has been so positioned that when the bit 5 is deflected therefrom it will tend to direct the well bore more nearly toward the vertical than it was before the cement plug 3 was positioned. In other words, the bit may be used to deflect a hole from the vertical or to bring the hole back to the vertical, depending upon the circumstances of any particular case.

The particular construction of the bit is best seen in Figs. 1, 2 and 3 wherein the operating stem 8 is shown as threadedly connected to the bit body 15. This body is of peculiar formation and has its lower end formed with the separated shank portions 17 and 18. These shank portions are spread apart to provide a recess 20, which is to receive the shank 21 of the bit blade 22. This construction is best seen in Figs. 2 and 3. A pivot pin or shaft 24 projects through suitable openings in the shanks 17 and 18 and 21, so that the blade is capable of a swinging movement relative to the body 15. In order to control this swinging movement a set screw 24 is provided on the heel 25 of the blade 22 and is arranged to abut against the shoulder 26 on the body 15. It seems obvious that by adjustment of this set screw 24 the angular position of the blade 22 can be set with respect to the body 15. A similar set screw 28 may be provided on the front portion of the body 15 so that pressure can be brought against the shoulder 29 on the bit blade. By adjusting both of these set screws and turning them down tightly the exact angular position of the blade with respect to the body may be determined and fixed for any desired angle of deviation.

In order that flushing fluid may be circulated through the bit the body 15 is provided with a passage 30 which extends downwardly into the shanks 17 and 18 and then extends laterally therethrough into the chamber 31, which is formed in each of the shanks. This chamber 60 opens against the shank 21 of the blade 22 and if desired a ring packing 33 may be provided in each of these chambers so as to form a seal between the faces of the shanks. This packing may be of any desired type or configuration so long as 65 a seal under pressure will be formed. The pivot pin 24 is shown as having been welded in position in the shanks 17 and 18 by the band of welding material 35, but it may be positioned in any other manner desired.

The shank 21 of the bit blade 22 is formed with a recess 36 which communicates with the chambers 31 and in turn with the passage 37 which extends downwardly through the bit blade and terminates in the discharge port 38 in the lower end thereof. In this manner a continuous pas-

sage is formed from the operating string 8 to the cutting edge 6 of the spudding bit.

The blade 22 is of a particular construction which is seen in detail in Fig. 1 as embodying the front face 40 and the back face 41. These faces are opposed to each other in order to form the body and while they are substantially flat in transverse elevation the face 40 is curved but very slightly along the longitudinal axis of the blade, so that the cutting edge 6 of the blade is closely adjacent the outer edge 42 of the front of the blade portion, whereas the back face 41 is curved materially as seen in Fig. 1, until it meets with the face 40 at the cutting edge. In this manner the blade assumes the form of a chisel with the cutting edge 6 off center or offset with respect to the center line of the bit. The object of this offset position of the blade is readily apparent from the showing in Figs. 4 and 5, because it is desirable to spud the bit against the cement plug 3 or against the well bore formation in order to start an opening in the desired deflected direction.

It will be understood that this bit is not rotated but is what is known as a spudding bit, which is manipulated by raising it and dropping it sharply against the formation. The weight of the operating stem 8 added to the weight of the bit strikes a substantial blow which drives the cutting edge 6 into the formation. In practice, if it is intended to control the direction of the deflection, then the bit is attached to the operating string and oriented into the hole so that the operator knows the direction at which the cutting edge 6 will penetrate the cement plug and the well bore. There is no rotation while this bit is being lowered into the hole and in this manner the well can be deflected in any direction of the compass desired and the steepness of the angle of deflection can be determined by adjusting the set screws 24 and 28, if a steeper angle of deflection is desired than the difference between the opposed faces 40 and 41.

In some instances it may not be desired to deflect the hole in any particular direction and if this be true the bit can merely be lowered into the well and then spudded a sufficient amount to insure that a deflecting opening has been formed.

It will be obvious that the circulating liquid is discharged on the front face and tends to wash the formation away in the direction in which the deflection is to occur. This is of particular advantage in soft formations because it assists in the deflecting of the bit and removing the material in front of the bit.

Broadly the invention contemplates a bit by which a side tracking or deflecting operation can be readily performed and once the deflected opening is started the bit can be removed and the drilling of the well bore continued in an ordinary manner. While a cement plug has been shown as the deflecting body against which the bit will be moved, it is to be understood that any type of whipstock or other obstruction may be used.

What is claimed is:

1. A spudding bit including a body and a blade portion, interfitting shanks on said portions, a pin passing through said shanks whereby said blade may be pivoted relative to said body, and a passage extending through said body, blade and shanks.

2. A deflecting tool for spudding in the bottom of a well bore to form a cavity inclined in a predetermined direction with respect to the axis 75

- of the well bore so that the cavity can be thereafter used to deflect a rotary drilling bit which comprises in combination a string of drill pipe, a bit head fixed to the lower end thereof, a wedge like blade member connected to said head, said blade having a cutting edge which is a straight line, means to fix said blade in an off center position so as to divert the bit and form a cavity at an angle to the axis of the well bore when the blade is forced longitudinally into the bottom of the well bore, said means being adjustable to predetermine the angle of deflection, and a discharge port for fluid on the outer face of said blade closely adjacent the cutting edge.
5. A deflecting tool for spudding in the bottom of a well bore to form a cavity inclined in a predetermined direction with respect to the axis
- of the well bore so that the cavity can be thereafter used to deflect a rotary drilling bit which comprises in combination a string of drill pipe, a bit head fixed to the lower end thereof, a wedge like blade member connected to said head, said 5 blade having a cutting edge which is a straight line, means to fix said blade in an off center position so as to divert the bit and form a cavity at an angle to the axis of the well bore when the blade is forced longitudinally into the bottom 10 of the well bore, said means being adjustable to predetermine the angle of deflection, a discharge port for fluid on the outer face of said blade closely adjacent the cutting edge, and interconnecting passages thru said drill stem, bit head, and 15 blade to supply fluid to said port.
